VACUUM CLEANER

Agnes Juelson, Chicago, Ill.

Application November 23, 1931, Serial No. 576,909

9 Claims. (Cl. 183—36)

The invention relates to vacuum cleaners and has as its primary object the provision of improved means for separating dirt and dust from air.

5 A particular object of the invention is to provide an improved vacuum cleaner which is constructed in such manner that it is not necessary to employ a closely woven fabric, to separate dirt and dust from the air.

10 Another particular object of the invention is to provide an improved vacuum cleaner of the bag-less type.

15 Other objects and advantages will become apparent as the following detailed description progresses, reference being had to the accompanying drawings, wherein:

Figure 1 is a vertical central section taken through a vacuum cleaner which embodies the invention.

20 Fig. 2 is a fragmentary side elevation of the improved vacuum cleaner.

Fig. 3 is a section taken on line 3—3 of Fig. 1.

Fig. 4 is a section taken on line 4—4 of Fig. 1.

Fig. 5 is a section taken on line 5—5 of Fig. 1.

25 Fig. 6 is a section taken on line 6—6 of Fig. 4.

Fig. 7 is a fragmentary plan view of a separator plate which forms part of the improved vacuum cleaner, and

Fig. 8 is a section taken on line 8—8 of Fig. 7.

30 Referring to the drawings wherein a preferred embodiment of the invention is illustrated, the reference character 10 designates generally a housing which encloses the operating parts of the device. The housing 10 is mounted upon castors 11, or the equivalent, and may be drawn across a floor to position it with respect to the surface which is to be cleaned. The housing 10 comprises housing members 12 and 13, the castors 11 being secured to the housing member 12. The housing

40 member 12 encloses a separating chamber 14 in which the dirt and dust collect. The housing member 13 encloses an electric motor 15 and also provides passages through which the air which has been cleaned escapes from the housing

45 10. A handle 17 pivoted to the housing member 13 provides means whereby the improved vacuum cleaner may be handled.

The upper edge of the housing member 12 is provided with a bead 18 which is aligned with a 50 bead 19 formed on the lower edge of the housing member 13, the beads 18 and 19 being adapted to clamp the marginal portion of a separator disc between them. The separator disc or plate is identified by the reference character 20.

55 The housing member 13 is detachably secured

to the housing member 12 by means comprising a split ring 22. The split ring 22 comprises segments 22a and 22b, segment 22a being provided with a lug 22c detachably engageable with the segment 22b to secure the segments to each other. The segment 22a is also provided with a lever 23 pivoted to a bracket 24 which is rigidly secured to the segment 22a. Pivoted to the lever 23 is a link 26 which is engageable with a hook 27 rigidly secured to one end of the segment 22b. It will be readily understood that when the lever 23 is in the position wherein it is illustrated in Fig. 4, the link 26 co-operates with the hook 27 and secures the split ring 22 around the housing members 12 and 13 in such manner that the split ring co-operates with the beads 18 and 19 to clamp the housing members 12 and 13 to each other. It will be noted that the segments 22a and 22b are preferably V-shaped in cross section so that they tend to urge the beads 18 and 19 toward each other when the split ring 22 is tightened around the housing. And it will be readily understood that the lever 23 may be angularly displaced in a counter clock-wise direction (Fig. 4) around its axis so that the link 26 may be disengaged from the hook 27. When the link 26 is disengaged from the hook 27, the split ring 22 may be removed from the housing and the housing member 13 and the part secured within it may be lifted from the housing member 12. This permits access to the separator chamber 14.

Disposed within the housing member 13 and rigidly secured to it is a bracket 30 which has a cylindrical wall 31 provided with a plurality of apertures 32. Formed integral with the wall 31 and closing the lower end of a chamber 33 in which the motor 15 is mounted is a plate 34. A plurality of vertically disposed bolts 35 have their ends screw-threaded into bosses 36 formed integral with the plate 34. The bolts 35 extend through bores 38 formed in the housing 40 of the electric motor 15, nuts 41 screw-threaded upon the bolts 35 being adapted to hold the housing 40 in an adjusted position upon the bolts.

The motor 15 comprises an armature 43 mounted on a vertically disposed shaft 44 which has its lower end rotatably journaled in a boss 45 preferably formed integral with the plate 34. The upper end of the shaft 44 is rotatably journaled in a bearing 47 formed integral with radially extending arms 48 which are formed integral with the cylindrical wall 49 of a bracket which is designated generally by the reference character 50. The upper ends of the bolts 35 are secured in bosses 48a formed integral with the

arms 48. The lower end of the wall 49 flares outwardly and is provided with an annular flange 51 seated in an annular groove 53 formed in the bracket 30. Any suitable means is provided for securing the bracket 50 to the bracket 30. The construction being such the bracket 50 may be detached from the bracket 31 so that the bracket 50, the motor 15 and a fan 55 may be lifted from the bracket 31 as a unit.

10 The cylindrical wall 49 of the bracket 50 is preferably provided with a plurality of apertures 56 and the top wall of the housing member 13 is preferably apertured as at 57. This construction permits air to flow through the apertures 15 32 up into the upper part of the housing member 13 to be discharged from the housing through the aperture 57. Part of the air will pass through the apertures 56 and cause sufficient circulation of the air around the motor 50 to prevent it from 20 over-heating.

The separator plate 20 is preferably frustro-conical in form and is preferably provided with a relatively large central opening 60. An annular flange 61 formed integral with the separator 25 plate 20 encircles the opening 60 and seats against an annular gasket 62, the gasket 62 being clamped between the flange 61 and the bracket 31.

The separator disc or plate 20 is provided with a plurality of radially extending slots 64. The 30 slots 64 are formed by stamping small flanges 65 from the disc or plate 20 (see Figures 7 and 8), each flange 65 comprises an inclined portion 65a formed integral with the disc or plate 20 and a portion 65a which extends substantially parallel to the adjacent part of the body portion of the disc or plate 20. The portion 65a of the flanges 65 are spaced from the under surface of the disc or plate 20 a slight distance so that air may escape from the chamber 14 up through the slots 35 64 into the housing member 13.

40 The openings formed by the slots 64 are preferably 1/64th of an inch or less in width. However, in some instances it may be desirable to have these openings more than 1/64th of an inch 45 wide. The slotted portion of the plate 20 is preferably disposed at an angle of approximately 7° to the horizontal.

The fan 55 preferably comprises three grooved blades 55a, the forward surface of each blade 50 55a being preferably a parabolic curve. The fan is preferably of smaller diameter than the opening 60 formed in the plate or disc 20. The upper surfaces of the blades are preferably flat. Each 55 of the blades 55a is of greater height adjacent the axis of rotation of the fan than it is at its outer end, the construction being such that when the fan is rotated in a counter clock-wise direction (Fig. 4) it creates a partial vacuum beneath the central portion thereof and drives air 60 outwardly from its axis of rotation toward the slots 54, the air being given a whirling motion so that it passes the slots in the direction indicated by the arrow in Figure 8.

Disposed beneath the fan 55 and the separator disc or plate 20 is a deflector plate 71 which 65 is rigidly secured to a tubular member 72 adapted to be seated in a sleeve 73 which is rigidly secured to the housing member 12 by bolts 74, or the equivalent. As indicated at 76 in Figure 1, 70 a bayonet slot connection is provided between the tubular member 72 and the sleeve 73 so that the tubular member 72 is detachably secured to the sleeve 73. Obviously, after the housing member 13 has been removed from the housing member 12, the deflector plate 71 may be lifted out

of the housing member 12 so that the dust and dirt collected in the housing member 12 may be removed therefrom.

The tubular member 72 and the sleeve 73 communicate with an intake pipe 78 which is secured to the housing member 12 by the bolts 74. The pipe 78 has a horizontal portion 79 extending beneath member 12 and it will be readily understood that suitable attachments may be secured thereto when the improved machine is to be operated.

80 The deflector plate 71 preferably has a mushroom shape and comprises a central frustro-conical portion 71a which has a central opening 71b aligned with the opening through the tubular member 72. The frustro-conical member 71a is inverted so that its wall, which is preferably formed from sheet metal, slopes upwardly from the tubular member 72 toward the separator disc or plate 20. It will be noted that the incline of 90 the wall of the frustro-conical member 71a is approximately equal to the incline of the lower edges of the blades 55a (see Fig. 1). The diameter of the base of the frustro-conical member 71a is preferably less than the inside diameter 95 of the slotted area of the plate or disc 20.

95 The deflector plate 71 also comprises a frustro-conical member 71c which is formed integral with the frustro-conical member 71a. The wall of the frustro-conical member 71c slopes downwardly from the base of the frustro-conical member 71a and is provided at its outer edge with a downwardly extending flange 71d. The diameter of the deflector member 71 is preferably greater than the diameter of the slotted portion 105 or area of the separator plate or disc 20, the slotted portion of the plate or disc 20 being substantially annular in form. The members 71a and 71c are preferably inclined at an angle of 110 approximately 20° to the horizontal.

115 The operation of the above described vacuum cleaner is substantially as follows. The motor 15 is connected to any suitable source of electrical energy and a suitable attachment, such as a hose and nozzle, is attached to the intake pipe 120 78. Air is drawn through the nozzle and hose (not shown) into the intake pipe 78, and then through the sleeve 73 and the tubular member 72 to the fan 55 which drives it outwardly as described above so that it passes beneath the 125 slots 64 in the direction indicated by the arrow 70 in Figure 8. In view of the pressure which obtains in the chamber 14, air escapes from the chamber through the slots 64 but the dust and dirt drawn into the device through the intake 130 pipe 78 falls downwardly over the frustro-conical portion 71c to the bottom of the housing member 12 where it is collected. After the improved cleaner has been used for some time, the split ring 22 is removed therefrom so that the housing member 13, together with the motor 15 and fan 55 may be removed from the housing member 12. The separator plate 20 and the deflector plate 71 are then removed from the housing member 12 whereupon the collected dust and dirt 135 may be removed from the chamber 14. The device is then reassembled and is ready for further use.

140 Access may be had to the motor 15 by detaching the bracket 31 from the housing member 13 and then unscrewing the bolts 35 from the bosses 36. The motor may be removed from the bracket 50 by removing the nuts 41 from the bolts 35. It will be noted that the nuts 41 co-operate with 145

150

shoulders 48a on the arms 48 to hold the motor housing 40 in place between the arms 48.

It will be noted that the bolts 35 are the only means, in this instance, for detachably securing the bracket 50 and the motor 15 to the bracket 30.

My improved means for separating finely divided particles of matter from air, or the like, is adapted to be employed in various devices. Therefore, the appended claims are limited to vacuum cleaners of the type described only to the extent indicated therein.

While I have shown and described certain embodiments of my invention, it is to be understood that it is capable of many modifications. Changes, therefore, in the construction and arrangement may be made without departing from the spirit and scope of the invention to claim all novelty inherent in my invention as broadly as possible, in view of the prior art.

20 I claim:

1. In apparatus of the kind described, means for separating finely divided matter from air, said separating means comprising a separating plate having numerous small apertures formed therein through which said air passes, a deflector plate extending beneath said apertures, a driven fan between said separating plate and said deflector plate, and a receptacle beneath said deflector plate for receiving said finely divided matter.

2. In apparatus of the kind described, a housing, means in said housing for separating finely divided matter from air, said separating means comprising a rigid member having numerous small apertures formed therein, a fan disposed in substantially the same plane as said apertures and adapted to advance air therethrough, and a deflector plate beneath said apertures and extending between said fan and a chamber formed in said housing for receiving said finely divided matter.

3. In apparatus of the kind described, a housing, means for separating dust and dirt from air advanced through said housing, said separating means comprising a frusto-conical separating plate having an annular area provided with numerous small apertures through which air passes on its way through said housing, a deflector plate having a frusto-conical portion disposed opposite to said annular area and spaced therefrom, and a driven fan provided with a plurality of blades disposed centrally of said annular portion, the outside diameter of said fan being less than the inside diameter of said annular portion.

4. In apparatus of the kind described, a housing, means for separating finely divided material from air passing through said housing, said separating means comprising a frusto-conical plate having numerous narrow slots formed therein through which said air passes on its way through said housing, a deflector plate spaced from said slots and extending over a chamber formed in said housing, said chamber receiving the finely divided material separated from the air passing through the chamber, and a driven fan between said frusto-conical plate and said deflector plate.

5. In apparatus of the kind described, a housing, and means for separating dust and dirt from air advanced through said housing, said separating means comprising a separating plate having

an annular area provided with numerous narrow slots approximately one sixty-fourth of an inch in width, through which slots the air passes on its way through said housing, a deflector plate disposed opposite to said annular slotted area and spaced therefrom, and a driven fan disposed centrally of said annular portion, the outside diameter of said fan being less than the inside diameter of said annular portion.

6. In apparatus of the kind described, a housing having a compartment for receiving dust and dirt from air advanced through said housing, and means for separating dust and dirt from air advanced through said housing, said separating means comprising a separating plate having numerous small apertures through which air passes on its way through said housing, a deflector plate between said separating plate and said compartment, said deflector plate forming a wall for one side of said compartment and defining an annular passage through which the dust and dirt passes to said compartment, and a driven fan disposed between said separating plate and said deflector plate.

7. In apparatus of the kind described, a housing, and means for separating dust and dirt from air advanced through said housing, said separating means comprising a separating plate having an annular area provided with numerous narrow slots less than one sixty-fourth of an inch in width, through which slots the air passes on its way through said housing, a deflector plate disposed opposite to said annular slotted area and spaced therefrom, and a driven fan disposed centrally of said annular portion, the outside diameter of said fan being less than the inside diameter of said annular portion.

8. In apparatus of the kind described, a housing having a compartment for receiving dust and dirt from air advanced through said housing, and means for separating dust and dirt from air advanced through said housing, said separating means comprising a separating plate having an annular area provided with numerous small apertures through which air passes on its way through said housing, a deflector plate between said separating plate and said compartment, said deflector plate being of a diameter at least as large as the outside diameter of said annular area, said deflector plate co-operating with said housing to form an annular passage-way through which dust and dirt pass to said compartment, and a driven fan disposed between said separating plate and said deflector plate.

9. In apparatus of the kind described, a housing having a compartment for receiving dust and dirt from air advanced through said housing, means for separating dust and dirt from air advanced through said housing, said separating means comprising a separating plate having an annular area provided with numerous narrow slots, through which slots the air passes on its way through said housing, a deflector plate disposed opposite to said annular slotted area and spaced therefrom, said deflector plate co-operating with said housing to provide an annular passage through which dirt and dust passes to said compartment, and a driven fan disposed centrally of said annular portion.

AGNES JUELSON. 145
